CLAIM

The ornamental design for a turf aerator tool, as shown and described.

DESCRIPTION

FIG. 1 is a lower perspective view of turf aerator tool embodying my new design in an environment of use.

FIG. 2 is a lower perspective view thereof omitting the environment of use.

FIG. 3 is an upper perspective view of the turf aerator tool.

FIG. 4 is a front view of the turf aerator tool.

FIG. 5 is a back view of the turf aerator tool.

FIG. 6 is an upper view of the turf aerator tool.

FIG. 7 is a lower view of the turf aerator tool.

FIG. 8 is a left view of the turf aerator tool; and,

FIG. 9 is a right view of the turf aerator tool.

The broken lines of FIG. 1 are included for the purpose of illustrating an environment of use and forms no part of the claimed design.
